UNITED STATES PATENT OFFICE.

HERBERT F. OBERGHELL, OF RIVER FOREST, ILLINOIS, ASSIGNOR, BY MESNE ASSIGNMENTS, TO AUTOMATIC ELECTRIC INC., OF CHICAGO, ILLINOIS, A CORPORATION OF DELAWARE.

ADAPTER FOR TELEPHONE-SUBSTATION RINGERS.

Application filed April 20, 1923. Serial No. 633,538.

The present invention relates to adapters for telephone substation ringers, and more particularly to an adapter which provides means for assembling in a wood box wall telephone a ringer designed for a metal box wall telephone.

The object of the present invention is the production of an adapter or extension device whereby a ringer designed for a metal box wall telephone may be readily attached to a wood box wall type subscriber's telephone instrument without the necessity of making any alterations in the ringer mechanism.

This adapter is intended to permit of only one type of ringer being carried in stock, which type of ringer can be used on both kinds of wall type subscribers' telephone instruments. This adapter not only enables the same type of ringer to be used on both types of instruments, but also provides a very simple and efficient means of securing the ringer to the wood box type of instrument and is by no means a temporary makeshift, but is instead an improvement over prior means for securing a ringer to the wood box type of instrument, aside from the fact that it enables the one type of ringer to be used for either type of instrument.

The term "ringer" as used in the above paragraphs is defined as denoting an apparatus comprising two electro-magnets and an armature carrying a clapper rod provided with a bell clapper near its extremity. The apparatus is also provided with a pair of gongs mounted in the best suitable relation with the clapper rod and its clapper and adapted to produce an audible signal when struck by the bell clapper whenever the electro-magnets are connected to a predetermined source of current.

Referring now to the drawings, Fig. 1 is a front elevation showing the top section of a wood box wall telephone with the front cover removed and with a ringer mounted therein by means of two of the improved adapters. Figure 2 is a sectional view on the line AA of Fig. 1 and drawn as seen from the left; Fig. 3 shows the adapter unassembled. Figure 4 is a copy from the co-pending application of Erickson et al., Serial No. 549,733, filed April 5, 1922 and illustrates the lower portion of a metal box wall telephone with the cover removed having the ringer and the gongs inside the box. The

ringer, of course, is in all details identical to the ringer shown in Fig. 1 and designated R, the only difference being that the gongs and the ringer are entirely within the instrument and are assembled directly on the gong posts such as 4 and 5 in an inverted position so that the open part of them extends downwardly away from the ringer itself. In the instant case, however, the ringer is mounted in the upper part of the instrument and the gongs are on the exterior with the open part facing the ringer, as is the practice with wood box instruments. Figure 5 is a sectional view of the line BB of Fig. 4 and drawn as seen from the left. This last figure illustrates the manner of mounting the gongs directly on the gong posts as illustrated and described in the application referred to. The full utility of the present invention will be appreciated by considering that the same ringer can be used for two types of wall telephones, that is, for the wood type having the bells mounted outside of the box, as well as for the metal box type, having the bells mounted entirely inside the box.

The reference character 2 indicates the wood box, R denotes generally the ringer, 4 and 5 are the gong posts of the ringer, 6 is a machine bolt by means of which the left-hand gong 7 is secured, 8 is a hexagonal nut which is screwed on to the threaded portion of the stud or extension rod 11, Figs. 2 and 3, 9 is a hexagonal locking washer and can be seen best in Fig. 3, while 10 is a round centering washer.

Like parts are denoted alike throughout the drawings in order to facilitate the reading of the detailed description which is now to follow.

In order to assemble the adapting extension rods or studs, such as 11, on the ringer R, the centering washers, such as 10, are slipped onto the two studs in the position shown in Fig. 2. The studs are then screwed into the gong posts 4 and 5, after which the ringer is slipped in place with the extension studs extending through holes, such as hole 12, Fig. 2, in the instrument. The ringer is accurately positioned owing to the shape of the above mentioned centering washers, as can be seen best in Fig. 2. The hexagonal washers, such as 9, are next slipped over the adapting studs and the entire assembly is held together rigidly, upon the hexagonal

locking nuts, such as 8, being slipped over the studs and screwed tightly in place. The washer 9, it will be noted, is turned down at the corners in order to make it stick into the wood to prevent any tendency of the assembly to turn as the nut 8 is being tightened.

In order to complete the assembly, it is only necessary to place the eccentric gong 7 and its mate in position. The gongs are secured by the bolts, such as 6, which are threaded into the extension studs, as can be seen in Fig. 2.

The structure for supporting the bells inside the box is shown in Figs. 4 and 5 and will be readily understood without elaborate description. These drawings illustrate a metal box designated by the reference numeral 20 having a ringer R, which is in all details the same as the ringer R, shown in Fig. 1. In this case, however, the gongs are mounted inside the box and directly on the gong posts such as 4 and 5 shown in Fig. 4. In other words, the adapter shown in Fig. 3 is omitted and the gongs are mounted in an inverted position with the open part away from the ringer and attached to the gong posts by means of a machine bolt designated 6, as shown in Fig. 5.

It will be seen from the foregoing that the present invention provides means for assembling in a wood box wall telephone a ringer which is designed for use in connection with a metal box wall telephone.

Although the improved adapter has been described in connection with a wall telephone, it may be applied equally well to a ringer of the above type when the same is to be mounted in a bell box used in connection with a desk type telephone instrument.

40 I claim—

1. The combination, with a ringer having gong posts of a size suitable for mounting gongs in a telephone box with the open side

of the gongs away from the ringer, of adapters comprising extension rods attached to the gong posts, and having means for mounting the gongs on said rod on the outside of another type of telephone box with the open side of the gongs toward said ringer. 45

2. An adapter for use in mounting a ringer of the inside gong type having a gong support, in a telephone box of the outside gong type, said adapter comprising a stud threaded on one end and attached to said ringer gong support, a gong, means for supporting said gong on the other end of said stud, and means for securing said stud to said telephone box. 50

3. An adapter for use in mounting a ringer of the inside gong type in a telephone box of the outside gong type, normal gong supports on said ringer for mounting the gongs, said adapter comprising an extension rod attached to said normal gong supports between said gongs and said gong supports. 55

4. In a telephone box, a ringer, gongs therefor, said ringer being inside said box and having normal gong supports also inside said box, extension studs attached to said normal gong supports and extending through openings in said box, means for attaching said studs to said gong supports, means for attaching said studs to said box, and means for attaching said gongs to the outside ends of said studs. 70

5. In combination a ringer having gongs, means including gong posts for mounting said gongs on said ringer, stud bolt adapters attached to said gong posts and extending outside of said box, means for mounting said gongs on said adapters, and means including said adapters and said gong posts for supporting said ringer in said bell box. 75 80

In witness whereof, I hereunto subscribe my name this 16th day of April, A. D. 1923.

HERBERT F. OBERGFELL.
